United States Patent

Des. 236,600
Patented Sept. 2, 1975

236,600

SULKY HITCH

Warren L. Cameron, R.D. 1, Box 101,
Chester Springs, Pa. 19425

Filed Nov. 15, 1973, Ser. No. 416,260

Term of patent 14 years

Int. Cl. D12—01

U.S. Cl. D12—19

Fig. 1

Fig. 2

Fig. 3

Fig. 5

Fig. 4

FIG. 1 is a perspective view of a sulky hitch showing my new design;

FIG. 2 is a top plan view thereof;

FIG. 3 is a side elevational view thereof;

FIG. 4 is a rear elevational view thereof; and

FIG. 5 is a front elevational view thereof.

The broken line showing of the horse and sulky in FIG. 1 are for illustrative purposes only.

I claim:

The ornamental design for a sulky hitch, substantially as shown and described.
